(57) **CLAIM**

The ornamental design for a modification jig for firearm components, as shown and described.

DESCRIPTION

FIG. 1 is a perspective view of the modification jig for firearm components with this perspective view showing left

and right jig halves exploded away from each other and with large and small inserts exploded above the right jig half; FIG. 2 is a perspective view of that which is shown in FIG. 1, with the left and right jig halves brought together to form the jig and with the large and small inserts exploded above the jig;

FIG. 3 is a perspective view of that which is shown in FIG. 1, with the large insert included therein;

FIG. 4 is a perspective view of that which is shown in FIG. 1, with the small insert included therein;

FIG. 5 is an inside elevation view of the left jig half of FIG. 1;

FIG. 6 is a top plan view of that which is shown in FIG. 5; FIG. 7 is an outside elevation view of that which is shown in FIG. 5;

FIG. 8 is a bottom plan view of that which is shown in FIG. 5;

FIG. 9 is a rear end elevation view of that which is shown in FIG. 5;

FIG. 10 is a front end elevation view of that which is shown in FIG. 5;

FIG. 11 is an inside elevation view of the right jig half of FIG. 1;

FIG. 12 is a top plan view of that which is shown in FIG. 11; FIG. 13 is an outside elevation view of that which is shown in FIG. 11;

FIG. 14 is a bottom plan view of that which is shown in FIG. 11;

FIG. 15 is a front end elevation view of that which is shown in FIG. 11;

FIG. 16 is a rear end elevation view of that which is shown in FIG. 11;

FIG. 17 is a perspective view of the large insert of FIG. 1;

FIG. 18 is a right side elevation view of that which is shown in FIG. 17;

FIG. 19 is a bottom plan view of that which is shown in FIG. 17;

FIG. 20 is a rear end elevation view of that which is shown in FIG. 17;

FIG. 21 is a front end elevation view of that which is shown in FIG. 17;

FIG. 22 is a left side elevation view of that which is shown in FIG. 17;

FIG. 23 is a top plan view of that which is shown in FIG. 17;

(Continued)

FIG. 24 is a perspective view of the small insert of FIG. 1; FIG. 25 is a right side elevation view of that which is shown in FIG. 24; FIG. 26 is a bottom plan view of that which is shown in FIG. 24; FIG. 27 is a rear end elevation view of that which is shown in FIG. 24; FIG. 28 is a front end elevation view of that which is shown in FIG. 24; FIG. 29 is a left side elevation view of that which is shown in FIG. 24; and, FIG. 30 is a top plan view of that which is shown in FIG. 24. The broken lines in the drawings represent unclaimed environmental subject matter and form no part of the claim.
